UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed September 8, 1921. Serial No. 499,202.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a railroad draft gear of the friction type having a large frictional area.

Other objects of the invention will more clearly appear from the description of one embodiment of the invention hereinafter following.

In the drawing forming a part of this specification, Figure 1 is a horizontal section of a draft rigging embodying my invention. Figure 2 is a cross-section taken on line 2—2 of Figure 1. Figure 3 is a cross-section taken on line 3—3 of Figure 1. Figure 4 is a perspective view of one of the friction blocks.

Referring to the drawing, the numerals 10—10 indicate the draft sills, or other similar members of a railway car to which the draft rigging is applied. 11—11 are front stops secured thereto, and 12—12, the rear stops. The butt of a drawbar is shown at 13, suitably slotted for the passage of the key 14 which extends at its ends thru slots 15 formed in the draft members 10 and the front stops 11, the said slots being suitably elongated to permit the longitudinal movement of said key therein. The key 14 has a slidable slotted connection as indicated at 16 with the draft yoke 17. A shell 18 is mounted within the yoke pocket, the yoke and shell being suitably supported by the tie plate 19 which is appropriately secured, as for instance by the bolts 20, to the draft sills. A front follower is shown at 21 and engages the forward face of the plunger 22, which in normal position of the parts protrudes from the forward open end of the shell 18. Intermediate the plunger 22 and the springs 23, which are mounted in the rearward portion of the shell 18, is a plurality of friction blocks 24, each an oblique parallelogram in horizontal section and rel-

atively arranged in a staggered or zig-zag formation. The sides 25—25 of each of said friction blocks are substantially transverse to the axis of the shell and the ends 26—26 engage adjacent parallel friction faces 27—27 oppositely formed on the interior of the shell. Each of the opposite parallel friction faces 27—27 for a friction block are angular to the friction faces adapted to engage the ends of its adjacent friction block. 65

In the particular embodiment of the invention illustrated in the drawing, four friction blocks 24 are shown, the forward one being indicated at 28, the rearward at 29, the front intermediate at 30, and the rear intermediate at 31. Each of said blocks and the shell in the vicinity of the friction faces 27 are suitably cored, as indicated at 32—32. The rear friction block 29 rearwardly engages the front face of an internal follower 75 33. The forward end of the spring 23 is seated between the rear internal face 34 of the shell and the rear face 35 of the internal follower 33. As indicated at 36 in Figure 3 of the drawing, the internal follower is 80 provided with a slot for the reception of the spring 23 and the shell is open as at 37—37 to permit the insertion of parts on the assembling of the gear. On rearward movement of the drawbar, the front follower 21 85 moves the plunger 22 rearwardly, which in turn forces the front friction block 28 rearwardly and laterally along the adjacent guiding friction faces 27. During this movement the front friction block 28 will 90 be in sliding frictional engagement with the front face of the front intermediate friction block 30 which will, under the thrust of the front friction block 28, move rearwardly in frictional engagement with the friction faces of the shell adjacent its ends and laterally in a direction opposite to the lateral movement of the front friction block 28. The rear intermediate friction block 31 will, thru the impulse given it by 100 the front intermediate friction block 30, move in parallelism with the front friction block 28 and in turn the rear friction block 29 will move in parallelism with the front intermediate friction block 30. The movements of the friction blocks described will 105 all be resisted by the spring 23 thru its pressure against the internal follower 33, against which the rear friction block 29 will frictionally engage. Upon full compressing 110

movement of the gear the shoulders 38, 39 and 40, upon the rear face of the plunger 22 will engage respectively against the limiting stop faces 41, 42 and 43, provided within 5 the shell. In preferable arrangement the front follower 21 will engage the front end 44 of the shell simultaneously with the engagement of the plunger against the limiting stops. On forward movement of the draw- 10 bar the shell is drawn forwardly by means of the yoke, the action of the parts within the shell being similar to that occurring upon the rearward movement of the drawbar hereinbefore described. It will be observed 15 that in the action of the friction blocks, by reason of their zig-zag or staggered arrangement, alternate blocks will move in the same direction laterally and longitudinally, and that the odd numbered friction blocks, as 20 for instance the front block 28 and the rear intermediate block 31 will move laterally in one direction, while the even numbered friction blocks, as for instance the front intermediate block 30 and the rear block 29, will 25 move laterally in the opposite direction.

I have herein shown and described what I now consider the preferred manner of carrying out the invention, but the same is merely illustrative and I contemplate all 30 changes and modifications that come within the scope of the claims appended hereto.

I claim:

1. In a friction shock absorbing mechanism for railway cars, the combination with 35 a shell having internal friction faces; of pressure transmitting means; a spring resistance; and transversely arranged friction elements within the shell, said elements being interposed between said means and said 40 spring resistance, and each of said elements being provided at opposite ends with friction faces adapted to co-act with the friction faces of said shell.

2. In a friction shock absorbing mechanism for railway cars, the combination with 45 a shell having a plunger and a spring therein; of a series of blocks interposed between the spring and the plunger, each of said blocks having opposite pairs of parallel friction faces, one pair of said faces being inclined with reference to the longitudinal axis of the gear, said shell being provided with internal friction faces, said friction faces being arranged in sets, each set having 50 parallel contacts with alternate friction blocks, the said two sets of friction faces being oblique to each other.

3. In a friction shock absorbing mechanism for railway cars, the combination with 60 a shell; of a series of friction blocks; a plunger at one end of said blocks; and a spring at the other end thereof, the said blocks engaging at their sides, one with the other, the shell having friction faces engaging the ends of each of said blocks, the

friction faces for alternate blocks of the series being parallel to each other, and the adjacent friction faces of said shell being disposed angularly to each other.

4. In a friction shock absorbing mechanism for railway cars, the combination with 70 a shell: of a plunger and spring members within the shell; and a plurality of friction blocks interposed between the plunger and spring members, the shell being provided with friction faces for the ends of said blocks, said blocks having opposite pairs of parallel friction faces, said pairs of faces disposed obliquely with reference to each other, said blocks being arranged in alternate staggered relation, whereby each friction block has a lateral movement opposite to the lateral movement of its adjacent friction block.

5. In a friction shock absorbing mechanism for railway cars, the combination with 80 a shell having internal friction faces; of pressure transmitting means; a spring resistance; and transversely arranged friction elements within the shell, said elements being 90 interposed between said means and said spring resistance, and each of said elements being provided at opposite ends with parallel friction faces, said faces being inclined with reference to the longitudinal axis of 95 said shell and adapted to co-act with the friction faces of said shell.

6. In a friction shock absorbing mechanism, the combination with a friction shell provided with pairs of oppositely disposed 100 parallel internal faces, said faces being inclined with reference to the longitudinal axis of said shell, and the faces of adjacent pairs being reversely inclined; of pressure transmitting means; a spring resistance; and 105 a plurality of friction elements interposed between said means and said spring resistance, said elements being transversely disposed within the shell and provided with friction faces adapted to co-operate with the 110 friction faces of said shell.

7. In a friction shock absorbing mechanism, the combination with a friction shell provided with internal friction faces; of a pressure transmitting member; a spring resistance; and a series of friction blocks interposed between said spring resistance and said member, and arranged transversely within said shell, each of said blocks being provided with parallel friction faces at opposite ends, adapted to co-act with said friction faces of the shell, said end faces being arranged at an angle to the longitudinal axis of the shell, and the end faces of adjacent blocks of said series being reversely inclined.

8. In a friction shock absorbing mechanism; the combination with a friction shell having opposite internal walls thereof provided with friction faces, the friction faces of each of said opposite walls being arranged 130

in series with adjacent faces of said series disposed at an angle to each other; of a series of friction blocks arranged transversely of the shell, said blocks being provided with friction faces at their ends, cooperating with the friction faces of said shell; and pressure transmitting means acting to move the said series of blocks longitudinally of the shell and along the friction faces thereof, whereby movement of said

blocks relative to each other transversely of the shell, is effected.

In witness that I claim the foregoing I have hereunto subscribed my name this 26th day of Aug. 1921.

JOHN F. O'CONNOR.
